AUTOGRAPHIC REGISTER

Louis Jensen, Chicago, Ill., assignor to United Autographic Register Company, a corporation of Illinois

Application August 26, 1933, Serial No. 686,986

9 Claims. (Cl. 282—13)

This invention relates particularly to autographic registers and to improved mechanism for alining, feeding and refolding stationery.

The primary object of the invention is to provide a simple register of the recorder type in which the stationery is initially alined and advanced by an initial feed device and is provided with mechanism for insuring the proper refolding of a record strip within the machine.

10 Another object of the invention is to provide means for preventing the initial feed device from being improperly operated which might otherwise tear or get the stationery out of alinement.

A further object of the invention is to provide 15 a safety device which will interfere with the withdrawal of the record strip from the locked record compartment by anyone not having a key to the same.

Figure 1 is a perspective view of a machine embodying the invention; Fig. 2 is a broken longitudinal sectional view of the same taken as indicated at line 2 of Fig. 5; Fig. 3 is a broken sectional view taken as indicated at line 3 of Fig. 5, showing the feed mechanism in normal writing 20 position; Fig. 4, a similar view showing the feed mechanism in advanced position; Fig. 5, a broken plan view of the machine; Fig. 6, a transverse sectional view taken as indicated at line 6—6 of Fig. 5; Fig. 7, an enlarged broken detail view 25 showing the ratchet mechanism of the initial feed device; Fig. 8, an elevational view of the pivoted guide-member; and Fig. 9, a broken plan view of a portion of the throat leading to the record compartment.

30 35 In the embodiment illustrated, A designates a casing having a bottom wall A', a platen forming top wall A² which forms a closure for a supply compartment A³, and a closure member A⁴ for a record compartment A⁵; B, a skeleton cover provided at its front portion with a tear-off bar B'; C, a frictional device for pressing stationery strips together; and D, initial feed-mechanism equipped with a presser-member D' for holding the refolded record strip in proper position.

40 45 The casing A may be of any suitable construction, and is shown with a front wall 10 which is pivoted at 11 to the side walls 12. The door is held in position by the skeleton cover B. The supply compartment A³ is equipped with a front abutment member 13 which is attached to the bottom wall A' and serves to hold a packet of stationery 14 in proper position within the compartment. The closure member A⁴ is pivotally connected at 15 to the side walls of the machine and is equipped with a lock 16 to prevent

its being opened without a key. The cover A⁴ supports a pivotally mounted guide member 17, supported on a cross shaft 18 and serves to direct refolding of a record strip 14^a within the compartment A⁵. The guide-member is concavo-convex and its central portion 19 is struck forwardly to engage the bottom of the cover and limit its forward swing. The member is further provided at its lower side with teeth 20 whose use will be described below. A weight 21 urges the member downwardly against the stationery.

The skeleton cover B has a cut-out portion 22 which exposes stationery led over the platen A². It will be understood that a carbon strip 23 is interleaved between the stationery strips 14^a and, as shown in Fig. 6, the carbon strip is led from a carbon roll 24 supported within a housing provided in the supply compartment A³. A skeleton cover is pivotally connected to the casing at 25 and is provided at its rear end with the finger notch 26 to facilitate raising of the cover to insert a packet of stationery. The front edge B' of the skeleton cover forms a tear-off edge on which the issuing strip may be severed.

The frictional device C comprises an upper 30 presser-roll 27, which is journaled in a housing 28 provided in the front edge of the skeleton cover; and a lower presser-roll 29 journaled in a bifurcated rock arm 30 which is rigidly mounted on a rock-shaft 31 and is provided with an actuating arm 32. A spring 33 urges the lower presser-roll upwardly. These rolls normally press the stationery strips 14^a together so that when an issuing strip is withdrawn, a record strip is propelled into the record compartment A⁵ over 35 a throat-piece 34. Like the guide member, the lower front end portion of the throat-piece is provided with teeth 35. The stationery strips 14^a are provided at longitudinally spaced intervals with register perforations 14^b and if an attempt is made to withdraw the record strip by raising the skeleton cover and drawing the strip over the throat-piece, it will be understood that the teeth 20 and 35 will engage the perforations and prevent their withdrawal.

The feed mechanism D comprises a rock-shaft 40 journaled in standards 41 which are rigidly fastened to the casing by means of screws 42. The shaft is equipped with a pair of rigidly connected, upwardly extending arms 43 on which 45 are telescopically mounted register-pins 44 urged outwardly by means of compression springs 45. The pins are adapted to project upwardly through slots 46, provided in the throat-piece 34 and engage register perforations in the strips drawn for 50 55 60 65 70 75 80 85 90 95 100 105 110

wardly over the platen. The shaft is equipped on the outside of the casing with an operating handle 47 so that the pins may be rocked forwardly to initially advance and aline the stationery. A torsion spring 40^a urges the pins rearwardly. In order that the register-pins may be abruptly retracted at the forward end of their stroke, a rock-shaft 48, journaled in the standards 41, is equipped with U-shaped finger-pieces 49 which straddle and are adapted to depress the register-pins. The shaft is provided with an actuating arm 50 and a spring 51 which urges the finger-pieces downwardly. A latch 52 is pivotally connected to a standard at 53 and is urged forwardly by a leaf spring 54. As shown in Fig. 3, the latch-member 52 is adapted to hold the arm 50 up in inoperative position. The actuating arm 32, the arm 50 and the latch 52 are all actuated from the main rock-shaft 40 by means of a rigidly connected cam member 55. The cam member has an arm 55^a which is adapted to lift the arm 50 into latching position; an arm 55^b serves to momentarily release the presser-roll 29 so that the stationery strips may be alined free from frictional restraint; and the arm 55^c serves to release the latch 52 when the pins are rocked to their foremost position.

The above mechanism is similar to that shown in my co-pending application, Serial No. 642,643 filed November 14, 1932. However, in the present case, it may be noted that the lower end of the arm 32 is provided with an elbow 32^a so that during the forward and rearward movement of the pins, the presser-roll 29 is but momentarily released and this arrangement lessens the chance of the strips getting out of alinement.

Referring to Fig. 6, it will be seen that the lower front portion of the skeleton cover B is provided with a plate 56 having slots 57 through which the register pins 44 project after empaling the stationery. The slots are purposely somewhat wider than the pins and the pins are of a particular shape so that they will have less tendency to reengage the perforations on their return stroke (when a ratchet device is not provided on the operating handle). In the preferred construction, the pins are of the flat type with their upper corner portions well rounded.

In order to insure the pins being rocked forward sufficiently to enable the retracting mechanism to withdraw them from the stationery, a ratchet device of the character shown in Fig. 7 is preferably provided. This mechanism may comprise a bifurcated arm 58 which is rigidly mounted on the shaft 40 and straddles a ratchet arm 59 journaled on shaft 31. A leaf spring 60 is connected to the standard 44 by means of rivets 61 and is of sufficient length to hold the ratchet arm 59 out of engagement with the arm 58 during the return stroke of the latter. The arm 58 has a projection 62 which is adapted to release the arm 59 when the pins are returned to their rearmost position, and the arm 58 lifts the arm 59 into its inoperative position just as the pins reach their foremost position. A tension spring 63 is provided to urge the arm 59 downwardly.

When the record strips are propelled into the record compartment they have a tendency to re-fold into a zig-zag pack, as shown in Fig. 2. As explained above, the guide member 17 serves to direct this re-folding. However, the re-folded pack is rather loose and in order to compress it and hold the folds in proper position, a presser-member D' is provided. This member comprises a U-shaped arm 65 which is pivotally

connected at 66 to rearward extensions 44^a of the standards 44. A spring 67 urges the presser-member down into engagement with the pack. However, the main rock-shaft 40 is provided with an arm 68 to engage a roller 69 and raise the arm into the position shown in Fig. 4, whenever the pins are swung to their foremost position. The standards 44 are also provided with serrations or saw teeth 70, which extend forwardly into the compartment A⁵, to help prevent the refolded portions of the record packet from springing upwardly when the presser-member is raised.

The operation of the machine will be readily understood. After a set of forms have been filled in, the operating handle 47 is swung forwardly and the stationery strips are advanced and alined by the pins. During the first portion of the forward movement, the lower presser-roll is momentarily lowered, and at the extreme forward position the pins are retracted by the fingers 49. The pins are returned, retracted, to their rearmost position to engage the next set of perforations in the stationery which may then be advanced by hand.

The foregoing detailed description has been given for clearness of understanding only, and no unnecessary limitations should be understood therefrom, but the appended claims should be construed as broadly as permissible, in view 105 of the prior art.

I claim:

1. In an autographic register having a record compartment and a platen over which continuous-form stationery may be led from a zig-zag folded supply packet; an initial feed device for advancing said stationery into the record compartment; and means for directing the refolding of said stationery in the record compartment comprising a pivotally mounted guide member 110 and an upwardly and downwardly movable presser-member actuated by said feed device.

2. Mechanism as specified in claim 1, in which initial feed-device comprises an oscillatable member equipped with an arm for rocking said 120 presser-member.

3. Mechanism as specified in claim 1, in which the feed-device comprises an oscillatable member having a measured forward stroke, and means for preventing retraction of said oscillatable member until completion of its forward 125 stroke.

4. An autographic register comprising a casing having a platen-forming top and a record compartment; a rock-shaft journaled in said casing 130 and equipped with normally projected extensible register pins adapted to engage perforations in stationery-strips and advance the strips over said platen; a frictional device adapted to press said strips together so that withdrawal of an issuing strip will propel a record strip into said record compartment; and means for releasing and engaging said frictional device with the stationery during each forward and rearward stroke of the rock-shaft.

5. Mechanism as specified in claim 4, in which ratchet-means are provided to prevent the rock-shaft from being rocked rearwardly until the register-pins reach their foremost position.

6. An autographic register comprising a casing having a platen-forming top and a record compartment; an initial feed and alining device in said casing adapted to engage and advance continuous-form stationery strips over said platen less than a form length; a frictional device adapted to press said strips together so that with- 150

drawal of an issuing strip will propel a record strip into the record compartment; and means actuated by said feed device for releasing and reengaging the frictional device with the stationery during each forward and rearward movement of said feed device.

7. In a register: a casing provided with a platen over which a plurality of superposed stationery strips provided with register perforations may be led; a record-compartment having a throat through which a record strip may be received, said throat being equipped with teeth adapted to engage perforations in stationary retracted therethrough; and a guide-plate pivotally supported near the top of said record compartment adapted to assist in the refolding of said stationery therein, said guide-plate being equipped at its lower edge with teeth adapted to cooperate with said first mentioned teeth to prevent withdrawal of stationery through said throat.

8. In a register: a casing having a platen over which a plurality of continuous-form stationery strips may be led from a zig-zag folded supply packet, and a record-compartment adapted to receive and store one of said strips; frictional-means adapted to hold said strips in such frictional engagement that the withdrawal of an issuing strip will propel a record strip into the record-compartment; a presser-member pivotally mounted in said casing to assist in holding a refolded record strip; and oscillatable feed-means for initially advancing the strips and actuating said presser-member.

9. Mechanism as specified in claim 8, in which the casing is equipped near the presser-member with a saw-toothed standard adapted to be engaged by a refolded record-strip when said strip is released by the presser-member.
